(57) **CLAIM**

The ornamental design for an elbow pad, as shown and described.

DESCRIPTION

FIG. 1 is a front view of a elbow pad according to the invention. Excepting the longer broken line segments seen within the perimeter of the cap portion at the center of the elbow pad, the other broken lines in the figure views depict unclaimed portions of the design. The broken lines and portions they depict form no part of the claimed design. The longer broken line segments seen within the perimeter of the cap portion at the center of the elbow pad in FIG. 1 depict a seam line, which does not form part of the claimed designs.

FIG. 2 is a left-side view of a elbow pad according to the invention.

FIG. 3 is a top view of a elbow pad according to the invention; and,

FIG. 4 is a bottom view of a elbow pad according to the invention.
